INVENTOR:
BY *Victor J. Evans & Co.*
HIS ATTORNEYS.

UNITED STATES PATENT OFFICE

FABIAN MILLER, OF INGALLSTON, MICHIGAN

HAND PUNCH

Application filed July 31, 1931. Serial No. 554,358.

This invention relates to certain novel improvements in hand punches, and has for its principal object the provision of an improved construction of this character which will be highly efficient in use and economical in manufacture.

It is an object of this invention to provide an improved hand punch for forming characters in metal.

Another object of the invention resides in providing a hand punch for forming identifying characters in metal vehicle license plates.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a top plan view of a preferred construction of the invention;

Fig. 2 is a side elevational view on line 2—2 in Fig. 1; and

Fig. 3 is a sectional view on line 3—3 in Fig. 1.

In the drawings, which illustrate a practical and preferred embodiment of the invention, indicated generally at 10 and 11 are opposed jaws which are pivotally connected by the pintle 13, and urged apart by a spring 14 secured therebetween.

The jaw 10 is bifurcated to provide spaced arms 16 and 17, through apertures in which is extended a bolt 18 having a threaded end on which is a nut 19 that secures the bolt in position. A rotative male drum punch 20 is mounted on the bolt or pintle 18, between washers 23, and this drum is provided with raised letters 21, which are, in the present instance, arranged to form the names of various automobiles for reasons hereinafter mentioned.

Likewise formed by a bifurcation of the jaw 10 is a second pair of arms 24 and 25 which are aligned with but spaced from the arms 16 and 17. Provided in the arms 24 and 25 are slots 26 through which is extended

a bolt or pintle 27 having a threaded end on which is a nut 28, and rotatably mounted on the bolt or pintle 27, between washers 29, is a female drum punch 30 having sunken characters 31 formed therein, corresponding to the characters 21.

Having one end pivotally connected to the pintle 27, at the sides of the arms 24 and 25, are racks 32 which are pivotally mounted on the arms 24 and 25, as at 37, and these racks are provided with teeth 33 that mesh with the pinions 34 formed at the ends of the ears 35, the ears 33 being provided by the bifurcation of the jaw 11. The jaw includes an apertured boss 36 which extends between the ears 35 and through which the pintle 13 is extended.

In a typical use of the invention, the work, which may be a metal automotive vehicle license plate, may be disposed between the drums 20 and 30, the drums rotated to align corresponding characters thereon, and the jaws 10 and 11 may then be pressed toward each other. Since the ears 35 of jaw 11 are pivotally mounted on pintle 13, pressure exerted on the jaws 10 and 11 to force them together, will cause the pinions 34, formed at the ends of ears 35, to pivot the racks 32 about their mountings 37, and the pintle 27 and drum 30 will thus be forced

against the metal plate disposed between drum punches 20 and 31, the pintle 27 moving in slots 26. The characters 21 will, therefore, be forced through the metal plate into the characters 31 so that the image of the characters 21 will be cut or punched in the plate. In the typical use mentioned, the name of the automobile when punched into the license plate will be of value in preventing unauthorized transfer of the license plate, and assist in identification.

It will be understood, however, that any desired indicia or characters may be formed in the drums 20 and 30 and that the work upon which the punch may be used is not limited to license plates.

From the foregoing description it will be apparent to persons skilled in the art that the invention provides an improved rotary drum hand punch.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A hand punch comprising two pivotally connected opposed jaws, a pair of spaced arms on one of said jaws and a rotative drum punch between said arms, a second pair of arms on the last-mentioned jaw and provided with slots, a pintle extended between the second-named pair of arms and including portions projecting through said slots, a drum punch on said pintle between the second-named arms, racks pivotally mounted on the second-named arms and apertured to receive said pintle portions, and pinions on the other of said jaws meshing with said racks whereby the second-named punch may be forced toward the first-named punch and work inserted therebetween by forcing said jaws toward each other.
2. A hand punch comprising two pivotally connected opposed jaw members, pinions on one of said jaw members, two pairs of spaced arms on the other of the jaw members and one of said pairs of arms being provided with slots, a punch carried by one pair of arms, a pintle between the other pair of arms and including portions projecting through and beyond said slots, a punch on said pintle, racks pivotally mounted on the second-named arms, connected at one end to the pintle, and meshing at the other end with said pinions, so that said punches may be forced together against work inserted therebetween by pressure on said jaws.
3. A hand punch comprising two pivotally connected opposed jaw members, pinions on one of said jaw members, two pairs of spaced arms on the other of the jaw members and one of said pairs of arms being provided with slots, a rotative punch carried by one pair of arms, a pintle between the other pair of arms and including portions projecting through and beyond said slots, a rotative punch on said pintle, racks pivotally mounted on the second-named arms, connected at one end to the pintle, and meshing at the other end with said pinions so that said punches may be forced together against work inserted therebetween by pressure on said jaws.
4. A hand punch comprising two pivotally connected opposed jaw members, one of said jaws being bifurcated and spaced ears provided thereby, pinions at the ends of said

ears, two pairs of spaced arms on the other of the jaw members and one of said pairs of arms being provided with slots, a punch carried by one pair of arms, a pintle between the other pair of arms and including portions projecting through and beyond said slots, a punch on said pintle, racks pivotally mounted on the second-named arms, connected at one end to the pintle, and meshing at the other end with said pinions so that said punches may be forced together against work inserted therebetween by pressure on said jaws.

In testimony whereof I affix my signature.

FABIAN MILLER.
